UNITED STATES PATENT OFFICE

2,002,742

CONTAINER

Samuel Karasik, Oak Park, Ill., assignor to The
Curtiss Candy Company, Chicago, Ill., a corpora-
tion of Illinois

Application August 18, 1934, Serial No. 740,396

1 Claim. (Cl. 229—30)

This invention has to do with a container or box of simple structure and made from a blank of foldable sheet material.

Among the objects of the present invention 5 is the provision of:

A blank of simplified form having foldable sections so arranged that the number of operations required to construct a container may be reduced; and

10 An improved container of compact structure having a reinforced bottom and requiring a minimum amount of material.

The above and other desirable objects will become apparent upon reading the following description of the one form of the invention herein 15 described and by referring to the accompanying single sheet of drawings, hereby made a part of this application, and in which:

Figure 1 is a plan view of a blank which is 20 foldable into a container embodying the subject matter of the present invention; and

Figure 2 is a plan view of a container formed from the blank shown in Figure 1.

Like reference characters are used throughout 25 the following description and in the drawing for designating similar parts.

A blank 10 is formed usually of cardboard, though it may be of any other sheet material that is foldable and which has sufficient strength. It 30 is desirable that the material employed be such that the blank 10 may be cut from a larger piece of the material by means of a die and with little waste. Such die may score the surface of the blank 10 concurrently with the cutting of the blank. In Figure 1, the dotted lines within the 35 body of the blank 10 represent such scores or predetermined fold lines.

The blank 10 comprises two main sections 17 and 18 which form the upper and lower bottom 40 members of a box. Section 18 rests upon section 17 in an assembled box. Sections 17 and 18 in the present form of box are in the form of squares for convenience. Sections 17 and 18 are separated one from the other by a slit or cut 16.

Member 17 has at one edge a section 11 which 45 is separated by a score 23. Section 11 has a free short side from which a tab 13 projects separated from the member 11 by a score 28. Member 18 has at its edge a similar extension 12 separated by a score 24. Section 12 has a free short edge 50 from which a tab 14 projects, the tab being separated from the main body of section 12 by a score 27.

Sections 11 and 12 are separated one from 55 another by a score 15 which is in alignment with

slit 16. At its other edge, section 17 has an extension 19 separated by score 25. A tab 21 extends from the free short edge of member 19 being separated therefrom by a score 22.

Section 18 has an extension 20 separated from 5 it by a score 26. Member 20 is without a tab or tabs. Sections 19 and 20 are separated one from another by the slit 16 which divides sections 11 and 12.

One plan of folding the blank follows. Sections 11 and 12 are turned about the fold lines 23 and 24 into a plane normal to that of sections 17 and 18. The upper bottom section 18 is disposed upon section 17 as section 12 is folded upon the score 15. Sections 17 and 18 at this stage 15 will be in one plane, and sections 11 and 12 will be in planes normal thereto.

Sections 19 and 20 are next folded about the scores 25 and 26. The four vertical side walls of the container are thus formed from sections 11, 20 12, 19 and 20.

Tabs 13, 14 and 21 hold the side walls of the package in position. Tab 14 is bent upon score 27 to rest against the outer side of section 19; tab 21 is bent about score 22 to rest against section 20 at one end of its outer side; and the tab 13 is bent about score 28 to rest against the other end of the outer face of section 20. The tabs 13, 14 and 21 may be attached to the outer face 25 portions of the side walls upon which they rest 30 by means of glue, staples, or other conventional fastening means.

Any form of cover member may be used upon 35 the container. When desired, two of the members herein described may be telescoped one over the other. The outer member then should be of slightly larger dimensions. A container constructed in accordance with the present invention has a double bottom. The two side walls 11 and 12 are integral providing strength at the corner between them. The other corners of the box 40 are at the intersection of the side walls and the tabs 13, 14 and 21 are of adequate strength.

The blank is substantially rectangular, hence a 45 plurality of blanks may be cut from a larger piece of sheet material of suitable dimensions with a minimum of waste. The blank is assembled into a container with few operations. The two integral side wall sections 11 and 12 require no attaching means at their intersection 50 and are folded into proper position incidentally to the movement of one bottom section over the other. Fastening means or an adhesive is necessary at three corners only of the box.

What is claimed as new and is desired to be secured by Letters Patent of the United States is:

A blank for forming a box and comprising opposed members divided in part by a slit and in part by a score, each member having a main body and opposed extensions, one extension from each member being integral with an extension

from the other member and separated by such score, and the main bodies and the other extensions being separated by such slit, there being tabs upon three of said extensions and the fourth being without a tab.

SAMUEL KARASIK.
